UNITED STATES PATENT OFFICE.

GEORGE R. LE SAUVAGE, OF BUFFALO, NEW YORK, ASSIGNOR TO THE REPUBLIC METALWARE CO., OF BUFFALO, NEW YORK, A CORPORATION OF NEW YORK.

DESIGN FOR AN ASH CAN.

Application filed November 24, 1926. Serial No. 19,827. Term of patent 14 years.

To all whom it may concern:

Be it known that I, GEORGE R. LE SAUVAGE, a citizen of the United States, residing at Buffalo, in the county of Erie and State of New York, have invented a new, original, and ornamental Design for an Ash Can, of which the following is a specification, reference being had to the accompanying drawing, forming a part thereof.

In the accompanying drawings:—

Figure 1 is a side elevation of the ash can.
Figure 2 is a top plan view thereof.

I claim:—

The ornamental design for an ash can, substantially as shown.

GEORGE R. LE SAUVAGE.
